UNITED STATES PATENT OFFICE.

ANDREW E. WIRSING, OF MILWAUKEE, WISCONSIN.

ANTISKIDDING RAIL-CLAMP MECHANISM.

1,137,104.

Specification of Letters Patent. Patented Apr. 27, 1915.

Application filed October 29, 1914. Serial No. 869,171.

To all whom it may concern:

Be it known that I, ANDREW E. WIRSING, a citizen of the United States, and resident of Milwaukee, in the county of Milwaukee and State of Wisconsin, have invented certain new and useful Improvements in Anti-skidding Rail-Clamp Mechanism; and I do hereby declare that the following is a full, clear, and exact description thereof.

10 My invention consists in what is herein particularly set forth with reference to the accompanying drawings and pointed out in the claims of this specification, its object being to provide traveling cranes with simple, economical and efficient anti-skid rail-clamps, the same being especially designed for such cranes as are employed in handling coal.

20 Figure 1 of the drawings represents a side elevation of a fragment of a traveling crane, a fragment of an underlying track-rail and an anti-skid rail-clamp mechanism in accordance with my invention applied to the crane; Figs. 2 and 3, cross-section views 25 respectively indicated by line 2—2 and 3—3 in Fig. 1, with parts broken back, the weighted clutch-lever in Fig. 2 being elevated, and Figs. 4 and 5, cross-section views respectively indicated by lines 4—4 and 5—5 30 in Fig. 2.

Referring by numerals to the drawings, 6 indicates each of a pair of side sills of a traveling crane carriage. Bolted in connection with the sills and brackets therewith 35 are hanger-plates 7 and 8 for supports in the form of pins 9, said hanger-plates being in pairs. The pins are secured in their connection with the hanger-plates by split-keys or other suitable means, and hung loose on 40 said pins is a pair of frames to which a pair of horizontal tie-plates 10 are bolted. Bolted to each plate 10, to depend therefrom, is a bearing-box 11, and hung in the boxes is the pivot 12 of a pair of rail-grip- 45 ping clamp-members 13. The upper end of each clamp-member is fashioned to straddle a nut 14, and trunnions 15 of the nut engage recesses in branches of said clamp-member.

A right and left hand screw-spindle 16 50 engages the nuts 14, and bearing-boxes 17 for the spindle are bolted on horizontal members 18 of the frames aforesaid. Keyed fast on one end of the spindle 16 is a clutch-disk 19, and loose on said spindle is another 55 clutch-disk 20 having a shank 20'. Bolted to the clutch-disk 20 and its shank is a lever

21, and fast on the outer end of the lever is a weight 22. The opposing faces of the clutch-disks 19 and 20 are radially toothed and held in mesh by a set-collar 23 on the 60 spindle 16, said lever being adjustable to compensate for spread of the rail-tread, and also to compensate for wear of parts of the mechanism. As shown in Fig. 2, the disk-end 20 of the lever is held in clutch-engagement with the disk 19 by the set-collar 23, which collar is loosened and moved outward on the spindle 16 to permit adjustment of 65 said lever.

The lower jaw-ends of the clamp-members 70 are of suitable length and parallel to a track rail 24 upon which the carriage travels, the jaws being fashioned to grip upon the side of the rail-tread and to extend in under the same, as is clearly shown in Fig. 2. The 75 lever 21 being in the position shown, the screw-spindle 16 has been operated to move the upper ends of the clamp-members 13 outward and thus cause an inward gripping movement of their lower jaw-ends against 80 the interposed rail, the gripping pressure being in proportion to the length of said lever and the preponderance of the weight thereon. To release the rail-clamp, a lift 85 of the lever 21 is obviously necessary and the lifting operation may be accomplished by any suitable means, either mechanical or electric. The means herein shown is a cable 25 attached to the lever and trained on sheaves 26 suspended in brackets 27 attached 90 to outer hanger-plates 7 and 8 of the carriage, the cable being led to a point convenient to the operator of said carriage. A slight movement of the lever 21 is sufficient to release the grip of the jaw-ends of the 95 clamp-members 13 from the interposed rail, and the inwardly extending flanges 28 of the jaws remain under the tread of said rail, as guards to prevent track jumping by 100 truck-wheels of the carriage.

The frame carrying the clamp-mechanism being suspended loose on the pins 9 aforesaid, it is unaffected by lateral play of the carriage sills also aforesaid.

I claim:

1. A carriage, a framing with which the carriage has lateral play connection, a right and left hand screw-spindle for which the framing is provided with bearings, a weighted lever in adjustable connection with the 110 spindle, a pivot mounted in said framing, rail-gripping clamp-members on the pivot,

105

110

and spindle-engaging nuts held in ends of the clamp-members.

2. A pair of parallel carriage sills, hangers in connection with each sill, supports engaging the hangers, a framing in which the supports are loose, a right and left hand lever-controlled screw-spindle for which the framing is provided with bearings, a pivot mounted in said framing, rail-gripping 19 clamp-members on the pivot, and spindle-engaging nuts held in ends of said clamp-members.

3. A carriage, a framing with which the carriage has lateral play connection, a right and left hand screw-spindle for which the framing is provided with bearings, a weighted lever in connection with the spindle, a pivot mounted in said framing, rail-gripping clamp-members on the pivot, and 20 spindle-engaging nuts held in ends of said clamp-members.

4. A carriage, a framing therewith, a right and left hand screw-spindle for which the framing is provided with bearings, a 25 clutch-member fast on the spindle, a

weighted lever loose on said spindle and having a clutch-end engaging the clutch-member aforesaid, a pivot mounted in said framing, rail-gripping clamp-members on the pivot, and spindle-engaging nuts held in 30 ends of said clamp-members.

5. A pair of parallel carriage sills, a frame hung in connection with each sill, tie-plates connected to the frames, boxes attached to said plates, a pivot hung in the boxes, rail-gripping clamp-members on the pivots, other boxes with said frames, a lever-controlled right and left hand screw-spindle 35 engaging the latter boxes, and spindle-engaging nuts held in ends of said clamp- 40 members.

In testimony that I claim the foregoing I have hereunto set my hand at Milwaukee in the county of Milwaukee and State of Wisconsin in the presence of two witnesses.

ANDREW E. WIRSING.
